UNITED STATES PATENT OFFICE

162,746

WALL DISPLAY PANEL

Paul P. Oakler and Bernard L. Schmitzer,
Pittsburgh, Pa.

Application May 10, 1950, Serial No. 9,854

Term of patent 3½ years
(Cl. D80—1)

To all whom it may concern:

Be it known that we, Paul P. Oakler and Bernard L. Schmitzer, each a citizen of the United States, and each residing at Pittsburgh, in the county of Allegheny, and State of Pennsylvania, have invented a new, original, and ornamental Design for a Wall Display Panel, of which the following is a specification, reference being had to the accompanying drawing, forming part thereof.

Figure 1 is a perspective view of a wall display panel, illustrating our new design;

Figure 2 is a view showing an end elevation of said panel; and

Figure 3 is a view of the panel in vertical medial section.

We claim:

The ornamental design for a wall display panel as shown.

PAUL P. OAKLER.
BERNARD L. SCHMITZER.
